UNITED STATES PATENT OFFICE.

HARRY F. NILES, OF CHICAGO, ILLINOIS.

PACKAGE.

Application filed September 8, 1925. Serial No. 54,898.

My invention is concerned with packages, more especially with those designed to hold combustible articles, such as cigarettes, and is designed to produce such a package to which a strip of safety matches can be readily attached so that they will always be at hand ready to light the cigarette as soon as it is withdrawn from its original package.

It is further concerned with the combination of such a package, as above described, with such a strip of safety matches.

To illustrate my invention, I annex hereto a sheet of drawings in which the same reference characters are used to designate identical parts in all the figures, of which

Fig. 1 is a perspective view of a package embodying my invention having the strip of matches attached thereto;

Fig. 2 is a perspective view showing the package without the strip of matches; and

Fig. 3 is a central vertical section through the form shown in Fig. 1.

In an ordinary form, as shown, the cigarettes are enclosed in a tinfoil package *a* in which they are sealed by the government stamp *b*, and the tinfoil package is placed in a paper or cardboard container *c* which, except as hereinafter described, may be of any desired construction with the closed sides and bottom and the open top. To one of the sides or faces, I secure, preferably by gumming it thereto, the free end *j* of a tongue *h* formed by reducing the width of an adjacent side of the container *c*, thus forming a loop on that face so that when the cover

e of a strip of matches *f* is turned back, the end of the cover can be shoved up beneath the loop and slid along the face until it emerges from beneath the loop after which it is folded over as shown in Fig. 1 and the free end placed in the customary space provided between the fixed end *g* of the strip and the base or bottoms of the matches *f*.

With this arrangement, it will be obvious that the package of cigarettes having the loop *h* can be sold just as any ordinary package, and if the dealer makes a practice of furnishing a strip of matches with each package, as is not uncommon, the purchaser simply opens the strip and inserts it in the manner described, then closing it, and having thereafter the combined package of cigarettes and strip of matches so that when he extracts a cigarette the matches are at hand to light it.

What I claim as new, and desire to secure by Letters Patent of the United States, is—

A package for cigarettes, having a loop formed on a face thereof by extending a reduced portion of an adjacent side of the package across said face and securing the end of said reduced portion to said face near its adjacent edge, back of which loop the cover of a match strip may be passed to unite the cigarette package and the match strip.

In witness whereof, I have hereunto set my hand this 2nd day of September, 1925.

HARRY F. NILES.
